UNITED STATES PATENT OFFICE.

RUDOLPH WIRTH, OF CHICAGO, ILLINOIS, ASSIGNOR TO GUSTAV STEINMETZ, OF CHICAGO, ILLINOIS.

MACHINE FOR BRANDING AND POLISHING HAMS, BACON, OR THE LIKE.

SPECIFICATION forming part of Letters Patent No. 794,440, dated July 11, 1905.

Application filed January 16, 1905. Serial No. 241,317.

To all whom it may concern:

Be it known that I, RUDOLPH WIRTH, a citizen of the United States, residing at Chicago, in the county of Cook and State of Illinois, have invented certain new and useful Improvements in Machines for Branding and Polishing Hams, Bacon, or the Like, of which the following is a specification.

My invention relates to machines for applying brands, trade-marks, and similar indicia of origin or ownership to cured meats—such as hams, fitches of bacon, and the like—and has for its general object to provide a simple and reliable machine of this class capable of handling either hams or fitches of bacon and marking with uniform distinctness and accuracy widely-varying sizes of either.

Another object of the invention is to provide in intimate association with the branding mechanism a cleaning and polishing mechanism adapted to render clearer and more distinct the brand or mark, as well as to generally improve the appearance of the articles subjected to the machine.

Still another object of the invention is to provide a machine wherein the articles treated thereby may be handled with a maximum of expedition and despatch and in rapid succession.

Other minor objects and aims of the invention will appear later in the subjoined description.

My invention in an approved mechanical form is embodied in the machine shown in the accompanying drawings, wherein—

Figure 1 is an elevational view of one side of the machine. Fig. 2 is a similar elevational view of the opposite side of the machine. Fig. 3 is a front elevational view with certain parts in the foreground omitted for the sake of clearness. Fig. 4 is a rear elevational view. Fig. 5 is a detail perspective view of one of the saddles or seats supporting the hams during their passage through the machine. Fig. 6 is a detail end view of Fig. 5, partly broken out, to illustrate the means for adapting the device to seat sides or fitches of bacon; and Figs. 7 and 8 are detail isolated views of a

stop mechanism for preventing overthrow of the endless carrier.

The main operating parts of the machine are mounted on a suitable supporting-frame, which may in the simple form shown comprise a series of legs or uprights 10 on either side connected by longitudinal and transverse connecting bars or rods 11 and 12, respectively.

Mounted in and between the opposite ends of said frame are shafts 13 and 14, the former carrying just inside the side frame members a pair of large sprockets 15, and the latter similarly carrying a pair of large sprockets 16. Over the alined pairs of sprockets 15 and 16 are trained sprocket-chains 17, said chains carrying between them a series of rectangular supporting-plates 18. (Shown in detail in Figs. 5 and 6.)

These plates are preferably attached to and mounted on the chains through the provision of a pair of transverse angle-irons 19, secured across either end thereof on their under sides, said angle-irons each having near one end a pivot-pin 20, suitably journaled on the sprocket-chain, and near the other end having slot 21 engaged by a similar pivot-pin 22, carried by the chain, the play thus afforded facilitating the travel of the plates where the chains pass in a semicircular path around the sprockets at each end of the machine.

The plates constituting the upper section of the endless carrier are supported against the sagging of the chains by means of rollers 21^a, mounted on posts 22^a, supported on certain of the cross frame-bars 12, said plates being further supported against sagging on the lower run of the carrier by rollers 20^a on the ends of the pins 21 and 22, engaging the lower horizontal frame-bars 11, as shown in Fig. 3.

Surmounting each of the plates 18 is a saddle or seat 22 for hams, comprising, as shown in Fig. 5, a rectangular frame beveled and concaved on its upper and inner edges conformably to the general contour of the lower side of the ham and removably and adjustably secured to the plate, as by a pair of short angle-irons 23, fastened to opposite ends thereof and having slotted bases engaged by thumb-screws 24. To render the plates 18 inter-

changeable for either hams or bacon, the upper surface of the plate 18 is provided with a pair of upstanding pins or spurs 25, (clearly shown in Fig. 6 and indicated by dotted lines 5 in Fig. 5,) on which when saddle 22 has been removed the flitch of bacon is impaled, thereby rendering it stationary relatively to the plate during the branding and polishing operations, but readily removable by simply 10 lifting the same off the plate. In order to avoid interference between the spurs 25 and the saddle 22, the lower faces of the ends of the latter may be hollowed out to accommodate the spurs, as shown at 26 in Fig. 6.

15 Surmounting the main horizontal frame of the machine are a pair of parallel standards 27, in and between the upper ends of which is journaled a driving-shaft 28, carrying fast and loose pulleys 29 and 30, respectively, and 20 on its overhanging end a pinion 31. This latter meshes with and drives a large gear 32 on the same end of an underlying shaft 33, also journaled in and between the standards 27, which shaft has on its opposite end a crank-25 arm 34, that is connected by a connecting-rod 35 with one arm of a bell-crank lever 36, pivoted at 37 to one of the legs 10 of the machine-frame, the other arm of said bell-crank being joined by a connecting-rod 38 to an 30 arm 39, loosely hung on the overhanging end of shaft 14. The latter shaft has fast thereon behind the arm 39 a ratchet-disk 40, that is engaged by a pawl 41, pivoted on the arm 39, whereby the sprocket-chains and the supporting-plates carried thereby are given an 35 intermittent travel always in one direction under the oscillations of the arm 39, produced by the continuous rotation of the shaft 33.

The inner sides of the standards 27 are vertically grooved to form guideways for a cross-head 42, pendent from which and connected thereto by a universal joint is a branding-iron 33. This latter is of a common and well-known type and constitutes in itself no 45 part of the present invention. The cross-head 42 is suspended by a pair of vertical arms 43 and rollers 44 projecting laterally from the upper ends of the latter upon the periphery of a pair of duplicate cams 45, 50 mounted on the shaft 33. The height of the branding-iron 43 is roughly adjusted by providing a series of holes 43^a, 43^b, and 43^c in the arms 43 to receive the spindles of the rollers 44. A fine adjustment of the cross-head on its supporting-arms is secured by screw-and-slot connections 46 and 47 between said parts, as shown in Fig. 3. It is desirable to regulate the gravity effect of the branding-iron and the parts which support 55 the same, since the branding effect is produced solely by the gravity effect of said parts, and the clearness or distinctness of the brand depends upon imparting just the right amount of pressure to the ham through the 60 branding-iron. For this purpose I employ a

loose sleeve 48 on the shaft 33, said sleeve having a hub 49, to which is attached the upper end of a chain 50, the lower end of which is connected centrally to the cross-head 42, and from the opposite side of the 70 sleeve to that on which the upper end of the chain is wound there extends rearwardly an arm 51, carrying a counterweight 52 adjustable thereon. From this it will be seen that while the counterweight is not intended to and 75 does not overbalance the entire weight of the cross-head and branding-iron, yet it acts to overbalance a portion of said weight, the exact proportion being regulable by adjusting the counterweight on its arm so as to produce the desired gravity effect in the branding-tool.

As shown in the side elevational views, Figs. 1 and 2, the forward or receiving end of the machine-frame is inclined downwardly 85 slightly, so that with the endless plate-carrier traveling in the direction indicated by the arrows the plates successively pass around the forward sprockets and travel up a slight incline to a position beneath the branding-tool. 90 This facilitates the application of the hams or bacon to the tables by the operator standing in front of the machine. In view of the fact that the several supporting-plates must be brought to an exact position directly beneath 95 the branding-tool and arrested at such position during the branding operation it becomes quite essential in a machine of this character to provide means for preventing overthrow of the carrier upon its successive step-by-step 100 movements. A simple means for such purpose is illustrated in Figs. 1, 7, and 8, wherein 53 designates a circular member fast on shaft 14 inside of the ratchet-disk 40 and provided with a series of radial holes 54 (four as herein 105 shown) formed in its periphery, said holes being engaged by a sliding locking-bolt 55, Figs. 7 and 8, said bolt having a stem 56, slidably mounted in an axially-socketed slide 57, the stem 56 being backed by a compression-spring 110 58, housed in the socket of the slide 57 and having a laterally-extending pin or lug 59, possessing a limited play in a longitudinal slot 60 of the slide. The slide 57 is in turn slidably mounted in a tubular casing or sleeve 115 61 and has a laterally-projecting pin 62, operating in a longitudinal slot 63 in said sleeve 61, which pin 62 is engaged by the upper arm of a lever 64, pivoted at 65 to a suitable bracket-plate on the main frame and having a depending arm lying in the path of travel of a pair of tappets 66 and 67, fast on the connecting-rod 38. By reason of this construction it will be seen that when the lever 64 is struck by the tappet 66 on the idle or return movement 120 of the pawl 41 the slide 57 and locking-bolt 55 will be retracted from the ring or disk 53, thus freeing the shaft 14; but during the operative movement of the arm 39 and pawl 41 when 125 the carrier-chain is driven the tappet 67 will 130

strike the lever 64 from the opposite side, thereby advancing slide 57 and compressing spring 58 against the end of stem 56, the latter being held against movement by the engagement of the nose of the locking-bolt 55 with the periphery of the ring 53 until said ring has reached a position at which one of the holes 54 is opposite the locking-bolt, whereupon the spring 58 will instantly snap the latter into said hole, thereby locking the shaft 14 against further movement, this action occurring at the instant when a ham-supporting table has been brought directly beneath the branding-tool. The locking-bolt is retracted in the manner already described before the next advance movement of the endless plate carrier.

The machine as thus far described is complete for the purpose of applying the branding-marks, and its manner of operation in the performance of this function has already been sufficiently indicated, the intermittent or step-by-step travel bringing the ham or bacon supporting plates successively beneath the branding-tool and the latter rising and falling in properly-timed relation to coöperate therewith. I will next describe that portion of the machine whereby the hams or flitches after having been branded are cleaned and polished.

This latter operation is effected primarily by means of a series of cylindrical brushes 68, that are mounted to rotate at a high speed above and across the path of travel of the branded articles, said brushes when operating upon hams or similar articles having a rounded or convex upper surface, being also given a bodily oscillating movement substantially in the arc of a circle, so as to completely clean and polish the entire side of the ham exposed to their action. The brushes 68, as herein shown, are mounted in and between a pair of side plates 69, disposed above the parallel sides of the main frame and in rear of the branding-tool. These plates 69 are supported on a pair of links 70, said links being pivoted at their upper ends to the plates 69 and at their lower ends to the horizontal main frame members 11, whereby it is evident that a longitudinal reciprocating movement imparted to said plates must produce a compound to-and-fro and up-and-down movement of the latter, thereby causing the several brushes to move bodily in substantially semi-oval paths. The brushes 68 are preferably not journaled fixedly in the plates 69, but their journals are confined in vertical slots 69^a of said plates and are hung from vertically-adjustable uprights 71, carried by the latter by means of long tension-springs 72, whereby the brushes may readily adjust themselves vertically to any inequalities in the surface contour of the hams, at the same time maintaining a perfect cleaning and polishing contact with the latter by virtue of so much of their gravity effect as is not counterbalanced by the springs 72.

As above stated, the brushes 68 are most effective when rotated at a high rate of speed, and the means for thus rotating them simultaneously with their bodily-oscillating movement is more particularly shown in the side elevational view, Fig. 2, wherein 73 designates a sprocket-wheel fast on one end of shaft 33, behind the large gear 32, from which a chain 74 drives a small sprocket 75 on a short shaft 76, journaled in the frame member 11, said shaft having a large sprocket 77, in turn driving a chain 78, operating a similar pair of sprockets 79 and 80 on another short shaft 81, the sprocket 80 similarly, through a chain 82, operating another pair of sprockets 83 and 84 on a short shaft 85, the sprocket 84 in turn driving a short sprocket-chain 86, that passes over a sprocket 87, Figs. 3 and 4, on a short shaft 88, journaled in a bracket 89, carried by one of the oscillating plates 69. Shaft 88 also has a sprocket 90, that drives a chain 91, passing over a series of sprockets 92 on the brush-shafts. By reason of the fact that the small sprocket 87 is moved bodily in a path that is substantially the arc of a circle struck from the center of its driving-sprocket 84 said sprocket 87 is continuously driven, and thereby continuously drives, through the described connections, the shafts of the several brushes. It will be observed that the speed of the last-described gearing is multiplied several times between the primary driving-sprocket 73 and the driven sprocket-pinions 92 of the brush-shafts, whereby a comparatively slow rotation of the former is converted into a very high speed of the latter.

It simply remains to briefly describe the means for bodily reciprocating the brush-carrying frame. This means, as herein shown, consists of a grooved eccentric 93 on shaft 33, Fig. 1, that engages a roller 94 on the upper end of a lever 95, that is pivoted at 96 outside one of the standards 27 and at its lower end is connected by a link 97 with a rod 98, connecting the forward ends of the side plates 69. The rotations of the eccentric 93 obviously result in oscillating lever 95 on its pivot, thereby moving the brush-supporting frames bodily to and fro over the underlying carrier-plates, the links 70, supporting the latter, at the same time compelling a simultaneous rising-and-falling movement of the latter, which produces, as above stated, a path of travel for the brushes corresponding substantially to the outline contour of the upper surface of the hams.

It is evident that variations and modifications in respect to details of construction and relative disposition of parts might be made by those skilled in the art without departing from the principle of my invention or sacrificing any of the advantages thereof. Hence it is to be understood that I do not limit the invention to the machine as shown and described,

except to the extent indicated in specific claims.

I claim—

1. In a machine for branding hams and flitches of bacon, the combination with a vertically-reciprocable branding-tool, of an endless-chain carrier mounted to travel across the path of movement of said branding-tool, said carrier having mounted thereon a series of supports each comprising a plate having pins or spurs adapted to position a flitch of bacon thereon, and a saddle adapted to seat a ham removably secured to said plate, substantially as described.
- 15 2. In a machine for branding hams and flitches of bacon, the combination with a vertically-reciprocable branding-tool, of an endless-chain carrier mounted to travel across the path of movement of said branding-tool, said carrier having mounted thereon a series of supports each comprising a plate having pins or spurs adapted to position a flitch of bacon thereon and a saddle adapted to seat a ham removably secured to said plate and covering said pins or spurs, substantially as described.
- 25 3. In a ham-branding machine, the combination with a vertically-reciprocable branding-tool, of an endless carrier mounted to travel across the path of movement of said branding-tool, a series of ham-supporting plates mounted on said carrier, means for intermittently driving the latter so as to move said plates successively to a position beneath the branding-tool, and means for preventing the over-throw of said carrier comprising a fixed stop member fast on one of the carrier-driving parts, a spring-pressed slideable stop member co-operating with said fixed stop member, and automatic means for retracting said sliding stop member between successive movements of the carrier, substantially as described.
- 35 4. In a ham branding and polishing machine, the combination with a traveling carrier for the hams and means for applying the brand to the latter, of a brush mounted above said carrier across the path of travel of the hams, and means for imparting to said brush a combined rotary and bodily movement, substantially as described.
- 45 5. In a ham branding and polishing machine, the combination with a traveling carrier for the hams and means for applying the brand to the latter, of a brush mounted above said carrier across the path of the hams, and means for imparting to said brush a combined rotary and bodily-oscillating movement, substantially as described.
- 55 6. In a ham branding and polishing machine, the combination with a traveling carrier for the hams and means for applying the brand to the latter, of a brush mounted above said carrier across the path of travel of the

hams, means for rotating said brush, and means for simultaneously imparting thereto a bodily-oscillating movement over the convex upper surface of the hams, substantially as described.

65 7. In a ham branding and polishing machine, the combination with a traveling carrier for the hams, and means for applying the brand to the latter, of a brush mounted in elastically-supported journals above said carrier across the path of travel of the hams, and means for rotating said brush, substantially as described.

70 8. In a ham branding and polishing machine, the combination with a traveling carrier for the hams and means for applying the brand to the latter, of a brush mounted in elastically-supported journals above said carrier across the path of travel of the hams, means for rotating said brush, and means for simultaneously imparting thereto an oscillating bodily movement over the upper surface of the hams, substantially as described.

75 85 9. In a ham branding and polishing machine, the combination with a traveling carrier for the hams and means for applying the brand to the latter, of means for polishing the upper surface of the hams comprising a brush-carrying frame oscillatingly mounted on the carrier-frame above the carrier, and one or more rotary brushes mounted in said frame and adapted to sweep over the upper surface of the hams, substantially as described.

90 95 100 105 10. In a ham branding and polishing machine, the combination with a traveling carrier for the hams and means for applying the brand to the latter, of means for polishing the upper surfaces of the hams comprising a pair of plates disposed longitudinally of and above the sides of the carrier-supporting frame, links pivotally supporting said plates upon and above said carrier-frame, one or more rotary brushes journaled in and between said plates, and means for imparting a longitudinally-reciprocating movement to said brush-carrying plates, substantially as described.

110 115 11. In a ham branding and polishing machine, the combination with a traveling carrier for the hams and means for applying the brand to the latter, of means for polishing the upper surfaces of the hams comprising a brush-carrying frame, one or more rotary brushes mounted in said frame, tension-springs elastically suspending the journals of said brush or brushes in said brush-frame, and means for imparting a longitudinally-oscillating movement to said brush-carrying frame, substantially as described.
